BED FRAME SLAT

Edwin B. Watts, Lombard, Ill., assignor to Sealy,
Incorporated, Chicago, Ill.

Filed Nov. 26, 1971, Ser. No. 202,720

Term of patent 14 years

Int. Cl. D6—06

U.S. Cl. D6—198

FIG. 1 is a perspective view of a bed frame slat showing my new design, with a section cut away for conveniences of illustration; and

FIG. 2 is an end elevational view.

I claim:

The ornamental design for a bed frame slat, substantially as shown and described.
